US0D1008192S

(12) **United States Design Patent** (10) **Patent No.:** **US D1,008,192 S**
(45) **Date of Patent:** **** Dec. 19, 2023**

(54) **COMBINED WALL OUTLET WITH
WIRELESS DOORBELL**

(71) Applicant: **Shenzhen Dongshengxiang Technology Co., Ltd**, Shenzhen (CN)

(72) Inventor: **Yongfeng Zhang**, Linxiang (CN)

(73) Assignee: **Shenzhen Dongshengxiang Technology Co., Ltd**, Shenzhen (CN)

(**) Term: **15 Years**

(21) Appl. No.: **29/903,590**

(22) Filed: **Sep. 26, 2023**

(51) LOC (14) Cl. **13-03**

(52) U.S. Cl.

USPC **D13/152**

(58) **Field of Classification Search**

USPC D13/152, 102, 139.1, 199; D10/118.2,

D10/118

CPC G08B 3/10; H01R 13/6395; H01R 13/447;

H02H 11/005

See application file for complete search history.

Primary Examiner — Rhea Shields

(57) **CLAIM**

The ornamental design for a combined wall outlet with wireless doorbell, as shown and described.

DESCRIPTION

FIG. 1 is a front perspective view of component 1 showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof of component 2;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front, bottom perspective view, shown in an environment; and,

FIG. 18 is a front top, perspective view, shown in an environment.

The broken lines in the drawings illustrate the portions of the combined wall outlet with wireless doorbell, which form no part of the claimed design.

1 Claim, 18 Drawing Sheets
